Attorneys.

UNITED STATES PATENT OFFICE.

EVERETT B. STACKPOLE, OF SEATTLE, WASHINGTON.

CUFF.

1,300,038.

Specification of Letters Patent.

Patented Apr. 8, 1919.

Application filed December 28, 1916. Serial No. 139,354.

To all whom it may concern:

Be it known that I, EVERETT B. STACKPOLE, a citizen of the United States, residing at Seattle, in the county of King and 5 State of Washington, have invented certain new and useful Improvements in Cuffs, of which the following is a specification.

This invention relates to cuffs, and has for its object the provision of a cuff adapted 10 for use with cuff-fasteners of the type in which the meeting-edges of the cuff, in use, are embraced by the arms of a V-shaped plate having fastening means extending inwardly from one or both of its arms and 15 which project through one or both of the opposed button-holes to engage each other or in some other way operate to maintain the edges of the cuff in position in the V-shaped member. The cuff of the present 20 invention is especially suitable for use with a fastener of the type illustrated in my co-pending application Serial No. 137,328, filed December 16, 1916, and will be described in connection therewith.

25 The invention comprises a cuff whereof the edges which meet, in use, are provided with alined notches, so located that they will receive the angle or apex of the V-shaped clasp, and cause the outer surface of the angle of the V-shaped portion to lie substantially 30 flush with the meeting-edges of the cuff, so that the continuity of the edge-line of the cuff will not be broken by the V-shaped member, which, heretofore in embracing the edge of the cuff has necessarily 35 projected from the edge of the cuff for a distance equal to the thickness of the clasp. This is quite objectionable, since it causes considerable wear of the portion of the cuff 40 beneath the V-shaped member, and the projecting portion is constantly striking against articles about the wrist of the user. Also, it is very apt to catch in the lining of the coat-sleeve during movement of the cuff there- 45 through. By the use of my device these objections are overcome, and the appearance of the cuff and fastener is also much improved.

In providing such a cuff especially suitable 50 for use with the cuff-fastener of my above application it is sufficient to provide just one cuff button-hole, since there is but

one member on the inside of the V-shaped clasp which penetrates the cuff.

The invention will be better understood 55 by reference to the accompanying drawing, wherein

Figure 1 is a side view of the cuff before being folded;

Fig. 2 is a top view of the cuff, folded, 60 with its meeting-edges secured together by a cuff-clasp constructed according to my application hereinbefore referred to, part of the cuff being shown in section, for clearness; and

Fig. 3 is a side view of the folded cuff as shown in Fig. 2, part of the V-shaped clasp 65 being broken away.

The invention is shown as applied to one only of a pair of cuffs, but it will be readily 70 understood that the other cuff of the pair will be similarly constructed as to the notches, but that the positions of the button-holes will be reversed.

The cuff 1 is of the ordinary shape, and is 75 provided with the usual button-hole 2 and a button-hole 3 in a tab 4 for reception of the head of the wristband-button. But one cuff button-hole 5 is required, this, in the left-hand cuff illustrated, being opposite the edge 80 6 of the cuff which is provided with the tab 4. In alinement with the button-hole 5 and in the edges 6 of the cuff there are notches 7, of depth substantially equal to the thickness at the angle 8 of a cuff-clasp 9 of the 85 type which comprises a V-shaped plate adapted to receive the meeting-edges of the folded cuff, as clearly shown in Figs. 2 and 3.

The clasp illustrated is one of the form described in my prior application, and in 90 which one of the arms 10 of the plate 9 is provided with a pivoted button 11 having a prong 12 adapted to be inserted and withdrawn through the button-hole 5, the point 13 of the prong 12 piercing slightly the inside of the cuff opposite the button-hole 5, when in its inner position. To insure maintenance of the cuff in proper position, the opposite arm 14 may be provided with short prongs 15 forming between them a notch 95 into which the point 13 of prong 12 bears. To prevent inadvertent withdrawal of the prong 12, a spring 16 is secured to the button 11 beside the prong 12, and nests against

the inside of prong 12 during withdrawal of the latter. Its outer end becomes separated, however, from the prong 12 when the cuff-fastener is in position of use and assumes a position of rest.

The use of the device will be apparent. The cuff is folded in the ordinary manner, and its meeting-edges are inserted in the opening between the arms 10 and 14 of the 10 V-shaped member 9 so that the angle 8 thereof will fit into the notches 7, the prong 12 having first been withdrawn through the button-hole 5 by swinging the button 11 outward on its pivot. The button 11 is then 15 pressed inward against the arm 10 to the position shown in Fig. 2, whereupon the prong 12 will be moved through the button-hole 5 to its maximum inner position and its point 13 will be pressed into the fabric 20 of the portion of the cuff opposite the button-hole 5.

The outer surface of the angle 8 of plate 9 will thus lie flush with the meeting-edges of the cuff, as indicated in Fig. 3. While 25 one form of V-shaped fastener is illustrated, it will be apparent that so far as the use of the notches 7 is concerned the fastening means for the V-shaped member may be altered as desired. It is preferable that the 30 shape of the notches 7 conform to the cross-sectional shape of the plate 9 at its angle 8, although this is not entirely necessary.

The usefulness of the notches 7 and the improved appearance of the cuff will be ap-

parent without further description or dis- 35 cussion.

I claim:

1. A cuff for use with a V-shaped clasp of the type which embraces the meeting-edges of the cuff, having alined notches in 40 its meeting-edges, said notches forming a seat for the angle-portion of the clasp.

2. A cuff for use with a V-shaped clasp of the type which embraces the meeting-edges of the cuff, having alined notches in 45 its meeting-edges, said notches forming a seat for the angle-portion of the clasp and conforming in shape to the cross-section of said clasp at its angle.

3. A cuff for use with a V-shaped clasp 50 of the type which embraces the meeting-edges of the cuff and whereof one arm is provided with an inwardly extending fastening-member, said cuff having a notch in 55 each of its meeting-edges and a single buttonhole in alinement with said notches and adapted to receive the inwardly extending member of said clasp, said notches forming a seat for the angle-portion of the clasp.

4. A cuff for use with a V-shaped clasp 60 of the type which embraces the meeting edges of the cuff and whereof one arm is provided with an inwardly extending fastening-member, said cuff having a single 65 cuff-buttonhole adapted to receive the inwardly extending member of said clasp.

In testimony whereof I affix my signature.
EVERETT B. STACKPOLE.
